UNITED STATES PATENT OFFICE.

FRANKLIN GIFFORD, OF SPRINGFIELD, OHIO, ASSIGNOR TO JOSEPH G. JACOBS AND CHRISTIAN HANIKA, BOTH OF SAME PLACE.

HITCHING-BLOCK.

SPECIFICATION forming part of Letters Patent No. 296,739, dated April 15, 1884.

Application filed October 13, 1883. (No model.)

To all whom it may concern:

Be it known that I, FRANKLIN GIFFORD, of Springfield, county of Clark, State of Ohio, have invented a new and useful Improvement 5 in Hitching-Blocks, of which the following is a specification.

In the accompanying drawings, Figure 1 is a vertical sectional elevation, representing a hitching device of my invention. Fig. 2 is a 10 similar view taken through a line at right angles from that of Fig. 1, and Fig. 3 is a plan view of the hitch-bolt. In Fig. 4 I have illustrated a modification of the means used for holding the hitch-bolt firm at both ends of its 15 throw.

In each of these figures letters of like character indicate corresponding parts.

The object of the invention is to provide a fixed hitching device that when locked is 20 available for that purpose, thereby preventing preoccupation by intruders.

The invention consists in a throw-bolt provided at one end with a hook, slot, or other suitable receptacle for a hitching-strap, mechanical 25 means for throwing and retaining said throw-bolt in its locked and unlocked position, a key for throwing said bolt, and a metallic case for said bolt and its actuating mechanism, the configuration of said case being such that its 30 exterior surface presents nothing to which a reliable hitch can be made.

The casing is preferably constructed of two parts, $a a'$, held together with rivets $d d'$ and lugs $g g'$, and it is so shaped that a hitching 35 strap or rope cannot be made fast to it when it is arranged for disuse. The hitch-bolt b works in slideways $c c' c''$, and it is actuated by a weighted lever, $e e' f$, that is journaled in the casing $a a'$, as shown by the drawings. 40 The rock-shaft f is provided with a part, h , that may be of any suitable shape, for the accommodation of a key by means of which it can be oscillated to throw the hitch-bolt b . When this part h of the rock-shaft is constructed 45 as represented, it does not extend to the exterior surface of the casing $a a'$, and of course cannot present any catch for the hitching-strap to rest against. As the hitch-bolt b is

thrown out by the aforesaid key for purposes of hitching, a slot, i , extends beyond the exterior surface of the casing, through which the hitching-strap may be passed, and the weighted part e' of the lever e has passed the center of oscillation of the shaft f , and the hitch-bolt b is held to its unlocked position. 50 As the bolt b is drawn into the casing $a a'$, the weight e' passes to the reverse side of the center of oscillation of the shaft f and holds said bolt to its locked position. The part e of the lever $e e'$ passes through a slot, l , in the bolt 55 b , by means of which said bolt is actuated.

In place of the weight e' , a spring, q , may be used, into the pocket p of which a point, o , of the lever e may enter when the bolt b is out, and into the pocket p' of which the aforesaid point may enter when the bolt is drawn 60 into the casing.

The spring q may be secured to the inside surface of the casing $a a'$ by screws r , or otherwise to suit the taste of the constructor. 65

The key by means of which the bolt b is actuated is carried by the owner of the hitching device.

The casing $a a'$ is secured to the curbstone or some other stationary object by means of 70 lugs $m m$ and bolts that pass through perforations $n n$.

It is obvious that the casing $a a'$ may be cast in one instead of two parts, although the two parts seem now to be the most preferable mode 75 of construction.

Having thus described my invention, what I claim as new, and desire to secure by Letters Patent, is—

A stationary hitching device having a casing, $a a'$, a weighted lever, $e e' f$, a slide-bolt, $b i$, working in slideways in said casing, and a key for actuating said bolt, substantially as and for the purpose specified. 85

In testimony whereof I have hereunto set 90 my hand this 10th day of August, 1883.

FRANKLIN GIFFORD.
